US00D435233S

United States Patent [19]

Fountoulakis

[11] Patent Number: Des. 435,233

[45] Date of Patent: ** Dec. 19, 2000

[54] MILITARY CLUTCH

4,507,344 3/1985 Baughman 24/103
5,337,584 8/1994 Angel 24/103

[75] Inventor: Marcos Fountoulakis, Johnston, R.I.

Primary Examiner—Louis S. Zarfas

[73] Assignee: Dama Jewelry Technology, Inc., R.I.

Assistant Examiner—Catherine R. Oliver

[**] Term: 14 Years

Attorney, Agent, or Firm—Salter & Michaelson

[21] Appl. No.: 29/119,364

[57] CLAIM

[22] Filed: Feb. 28, 2000

The ornamental design for a military clutch, as shown and described.

[51] LOC (7) Cl. 02-07

DESCRIPTION

[52] U.S. Cl. D11/200

FIG. 1 is a perspective view of a military clutch showing my

**REEXAMINATION CERTIFICATE
ISSUED UNDER 35 U.S.C. 307
THE PATENT IS HEREBY
AMENDED AS INDICATED
BELOW.**

2

AS A RESULT OF REEXAMINATION, IT HAS BEEN
DETERMINED THAT:

5   The single design claim is cancelled.
